UNITED STATES PATENT OFFICE.

CHARLES HALLAUER, OF ROCHESTER, NEW YORK, ASSIGNOR TO ART IN BUTTONS, INC.,
OF ROCHESTER, NEW YORK, A CORPORATION OF NEW YORK.

DESIGN FOR A BUTTON.

55,037.

Specification for Design.

Patented May 4, 1920.

Application filed August 6, 1919. Serial No. 315,763. Term of patent 3½ years.

To all whom it may concern:

Be it known that I, CHARLES HALLAUER, a citizen of the United States, and a resident of the city of Rochester, county of Monroe, State of New York, have invented a new, original, and ornamental Design for Buttons, of which the following is a specification.

My design is represented in the accompanying drawing in which:

Figure 1 is a plan view of a button showing my new design.

Fig. 2 is a view showing the under side of the same.

Fig. 3 is a section on line 3—3 of Fig. 1.

The button is circular in shape and has an open work effect. The body of the button consists of five arms radially projecting from a central portion and uniformly spaced apart, the ends of the arms coinciding with the periphery of the button and extending a short distance along the same. The lines forming the boundary between each arm are uniformly curved and the outer ends of the

arms are connected by a beaded flange beveled on the center toward the inside, leaving an open space between the inner side of the flange and the curve forming the arms. The under edges of the arms are beveled.

A solid projection in the form of a frustum of a cone, slightly crowned at the top, extends upwardly from the arms to a distance slightly above the upper surface of the beaded flange. The under surface of the body of the button is slightly concave.

The button may be colored in any suitable manner.

The eyelet structure for the securing threads is a purely mechanical feature and forms no part of my design.

I claim:

The ornamental design for a button substantially as shown and described.

In witness whereof I have hereunto set my hand at Rochester, Monroe county, State of New York, this 23rd day of July, 1919.

CHARLES HALLAUER.
